INVENTOR

BY Victor J. Evans

ATTORNEY

WITNESS: Gerald Hennessy

Patented Sept. 21, 1926.

UNITED STATES PATENT OFFICE.

ABRAHAM LEWIS BERGER, OF STEUBENVILLE, OHIO.

SAFETY RAZOR.

Application filed December 30, 1925. Serial No. 78,408.

This invention relates to improvements in safety razors, the general object being the provision of blade holding means pivotally mounted for swinging movement upon the razor proper in order that the said blade may be readily and easily stropped. Another object of my invention residing in the provision of locking means included upon the holding means and for engagement with the pivot for the blade holding means in order that the same may be held rigidly in opened and closed positions.

With the above and other objects in view, the invention further includes the following novel features and details of construction, to be hereinafter more fully described, illustrated in the accompanying drawings and pointed out in the appended claims.

In the drawing:—

20 Figure 1 is an elevation of my invention. Figure 2 is a side elevation thereof.

Figure 3 is a diametric plan view of my invention when extended and ready for sharpening or stropping.

25 Figure 4 is a perspective of the blade per se.

Figure 5 is a rear elevation of the invention as completed and set up for use.

Referring to the drawing in detail, 30 wherein like characters of reference denote corresponding parts, the reference character 10 indicates an angularly shaped plate having one end closed and apertured as indicated at 11 in order that the reduced threaded end of a handle 12 may be selectively positioned and held rigidly with the rear side or end of the plate 10. Arranged upon the forward side of the plate 10 is a relatively large blade 13 including a forwardly offset portion 14 at an appropriate point in its height and having its outer side lying flush with the lower edge of the plate 10 while the lower extremity or edge of the plate 13 defining upwardly extending ears 45 15 upon its opposite sides and a plurality of cutout portions 16 arranged therebetween, the latter structure being prevalent in safety razors. The upper edge of the plate 13 being upwardly inclined as indicated at 17 while the corresponding side edge extending upwardly and abruptly as indicated at 18 with respect to the upper edge 17 and communicating therewith in

the manner as clearly illustrated in Figure 3 of the drawing.

A blade retaining means for the razor proper constituting a plate 19 bent upon itself as indicated at 20 and having a pivot pin 21 extending through one corner thereof for pivotally mounting the plate 19 as a whole upon the plate 13 in order that the said plate 19 may be swung upwardly and outwardly as clearly illustrated in Figure 3 of the drawing. The outer portion of the plate 19 forming an outwardly extending offset portion 22 while both of the said ends being bent inwardly one toward the other as clearly illustrated as at 23 in Figure 2 of the drawing. A razor blade 24 having a back 25, being substantially wedge-shaped in cross-section and defining shoulder 26 immediate the lower ends of its juncture with respect to the cutting edge 27 therefor in order that the said back 25 may be slid between the ends 23 of the plate 19 and the shoulders 26 preventing the blade 24 from riding upwardly within the plate 19.

In the foregoing description and accompany drawing it is clearly apparent and manifest that when the blade 24 is mounted within the holder or retaining means, as defined, the said retaining means with the blade may swing upwardly and outwardly in order that the said blade may be readily sharpened or stropped. The pivot pin 21 having a horizontal slotted portion therein, the purpose of which will be presently apparent.

A locking plate 27' having a tongue 28 upon one end having selective engagement 90 within the slotted portion of the pivot pin 21 and including spaced slotted portions 29 therein for the reception of the shanks of headed studs 30 secured within the immediate bent portion 20 of the plate 19 whereby 95 the said locking plate 27' being mounted for sliding movement and for locking the said plate 19 in the position as described and illustrated.

The blade 24 being relatively heavy and 100 strengthened, similar to that of straight edge razor and capable of being sharpened and stropped in a like manner and consequently one blade of this sort may last indefinitely.

The invention is susceptible of various

changes in its form, proportions and minor details of construction, and the right is herein reserved to make such changes as properly fall within the scope of the appended claims.

5 with respect thereto, a backed razor blade conforming to the configuration of the space defined between the ends of the retaining blade and inserted therebetween, means for pivotally mounting the retaining plate upon

55

Having thus described the invention, what is claimed is:

1. A safety razor of the character described exposing a blade upon its forward side and being substantially offset and providing upwardly extending ears adjacent its opposite ends, a blade holding plate positioned upon the aforementioned plate, means for pivotally mounting the blade holding plate to the razor proper to permit an upward and outward swinging movement thereon, and a locking plate carried by the blade holding plate for engagement with the pivotal mounting for rigidly retaining the latter in a desired position. 60

2. A safety razor of the character described comprising an angularly disposed plate having a relatively large plate secured upon its forward side, said relatively large plate having an offset portion lying flush with the lower edge of the angularly disposed plate and providing a pair of upwardly extending ears adjacent the ends and lower edges thereof, a blade retaining plate bent upon itself and having its outer extremity extending outwardly and inwardly therefrom while its remaining end extending inwardly oppositely disposed relation with respect thereto, a backed razor blade conforming to the configuration of the space defined between the ends of the retaining plate and inserted therebetween, and means for pivotally mounting the retaining plate upon the relatively large plate. 70

3. A safety razor of the character described comprising an angularly disposed plate having a relatively large plate secured upon its forward side, said relatively large plate having an offset portion lying flush with the lower edge of the angularly disposed plate and providing a pair of upwardly extending ears adjacent the ends and lower edges thereof, a blade retaining plate bent upon itself and having its outer extremity extending outwardly and inwardly therefrom while its remaining end extending in oppositely disposed relation with respect thereto, a backed razor blade conforming to the configuration of the space defined between the ends of the retaining plate and inserted therebetween, and means for pivotally mounting the retaining plate upon the relatively large plate. 80

4. A safety razor of the character described comprising an angularly disposed plate having a relatively large plate secured upon its forward side, said relatively large plate having an offset portion lying flush with the lower edge of the angularly disposed plate and providing a pair of upwardly extending ears provided adjacent the ends and lower edges of the relatively large plate, a blade retaining plate bent upon itself and having its outer extremity extending outwardly and inwardly therefrom while its remaining end extending in an oppositely disposed relation with respect thereto, a backed razor blade conforming to the configuration of the space defined between the ends of the retaining blade and inserted therebetween, means for pivotally mounting the retaining plate upon the relatively large plate, a pivot pin extending within the bent portion of the retaining plate and relatively large plate to permit an upward and outward swinging movement of the retaining plate thereon, locking means provided upon the bent portion of the retaining plate and engaging the pivot pin, a pivot pin extending within the bent portion of the retaining plate and relatively large plate and including a horizontal passage within the head therefor, and a locking plate slidably mounted upon the bent portions of the retaining plate and providing a tongue upon one end adapted for selective registration within the passages provided within the head of the pivot pin. 90

In testimony whereof I affix my signature. 100

In testimony whereof I affix my signature.

ABRAHAM LEWIS BERGER.
